UNITED STATES PATENT OFFICE.

WILLIS C. BRYANT, OF ELIZABETH, NEW JERSEY.

SIGNAL FOR RAILWAYS.

SPECIFICATION forming part of Letters Patent No. 744,716, dated November 24, 1903.

Application filed March 1, 1902. Serial No. 96,236. (No model.)

To all whom it may concern:

Be it known that I, WILLIS C. BRYANT, a citizen of the United States, residing at Elizabeth, in the county of Union and State of New Jersey, have invented certain new and useful Improvements in Signals for Railways, of which the following is a full and complete specification, such as will enable those skilled in the art to which it appertains to make and use the same.

The object of this invention is to provide an improved electrical block-signal system for railways, which may be used on all railways wherever such signal systems are required and which is particularly designed for preventing rear-end collisions, a further object being to provide a signal system of the class described which is particularly designed for use in railway-tunnels; and with these and other objects in view the invention consists in a railway signal system or apparatus constructed as hereinafter described and claimed.

The invention is fully disclosed in the following specification, of which the accompanying drawings form a part, in which the separate parts of my improvement are designated by suitable reference characters in each of the views, and in which—

Figure 1 is a diagrammatic view illustrating my improved electrical signal system for railways and the operation thereof; Fig. 2, an end view of a tunnel and a rear end view of the locomotive therein and shewing the part of my signal apparatus which is connected therewith; Fig. 3, a diagrammatic view of that part of the apparatus which is located in the cab of the locomotive; and Fig. 4, a detail view of different forms of a trolley-arm which I employ and which in practice is connected with the cab of a locomotive, said trolley-arm being provided with three trolleys, one of which is insulated from the trolley-arm.

In the drawings forming part of this specification, reference being made to Fig. 1, I have designated at a , a^2 , and a^3 three blocks of a railway provided with my improved block-signal system or apparatus, and it will be understood that the entire track or that portion thereof to which my improvement is applied is divided into blocks, any number of which may be employed, and said blocks

may be of any desired length. I have also shown at b that portion of the apparatus which in practice is placed in the superintendent's or train-despatcher's office, and on the block a^2 of the track I have indicated at c a locomotive and at d the rails of a track to which my improved signal system is applied, and in the practice of my invention I construct and arrange the various parts of my signal system or apparatus in the following manner:

Within the superintendent's or train-despatcher's office, which is designated in Fig. 1 by the reference character b , I place a plurality of electromagnets f^2 and f^3 , which equal in number the blocks into which the track is divided and which correspond therewith, and each of these magnets is provided with a pivoted armature f^4 , having a contact-point or limiting-stop f^5 , which operates in connection with a corresponding contact-point or limiting-stop f^6 , with which the corresponding magnet is provided, and each of said magnets is also provided with an electric light g , which is connected therewith by a wire g^2 and with one end of the armature f^4 by a wire g^3 , and the magnets f^2 , f^3 , and f^4 are grounded by means of wires m^2 , m^3 , and m^4 . Each of the armatures f^4 is also provided with a contact-point h , and below said magnets is a support h^2 , which carries a plurality of contact-points h^3 , and connected with these contact-points h^3 by means of branch wires h^4 is a main return-wire h^5 , which is connected with the rails of the track d and with a dynamo h^6 or any other suitable source or generator of electricity. I also employ a main conductor i , which extends the full length of the track and is also connected with the dynamo h^6 , and each section or block into which the track is divided is provided with two supplemental wires i^2 and i^3 , which run parallel with the main conductor-wire i , and the wires i^2 of the separate blocks or sections a , a^2 , and a^3 are connected, respectively, with the corresponding electromagnets f , f^2 , and f^3 in the superintendent's or train-despatcher's office, as shown in Fig. 1, while the wires i^3 of the separate blocks or sections are connected with the armature f^4 of the magnets f^2 , f^3 , &c., as clearly shown in said fig-

ures. I have also shown in Fig. 1 a locomotive *c*, which in the position shown in the drawings occupies the block *a*², and I have also indicated another locomotive at the right-hand side thereof, which occupies the block *a*. The locomotive *c* is provided with a trolley-arm *j*, which carries three trolleys *j*², *j*³, and *j*⁴, which operate in connection with the wires *i*³, *i*, and *i*², respectively, and the trolley *j*² is insulated from the trolley-arm *j*, and within the cab of the locomotive is placed an electromagnet *k*, which is in connection with the trolley-wheel *j*², which is insulated from the trolley-arm *j*, this connection being made by means of a wire *k*², and in the circuit formed by this wire is placed a red light *k*³, and the magnet *k* is grounded, as shown at *m*, and is also provided with a pivoted armature *k*⁴, with one end of which is connected a white light *k*⁵, this connection being made by means of a wire *k*⁶, and the armature *k*⁴ is also connected at its opposite end, by means of a wire *k*⁷, with the trolley-arm *j*. The details of the locomotive equipment are shown detached and on an enlarged scale in Fig. 3, and it will be understood that each locomotive operating on the track *d* is similarly equipped.

The wires *i*, *i*², and *i*³ may be arranged in any desired manner, and the trolley-arm *j* may be formed in any desired manner; but in Fig. 3 I have shown this trolley-arm provided with three branches which carry the trolleys *j*², *j*³, and *j*⁴.

The operation is as follows: When the locomotive *c* enters the block *a*², the contacts *j*², *j*³, and *j*⁴ engage the wires *i*³, *i*, and *i*², respectively, and the main conducting-wire *i* is always in circuit with the dynamo *h*⁶, and therefore always charged. As shown in Fig. 4, the contacts *j*³ and *j*⁴ of the trolley-arm *j* are in electrical connection with each other, while the contact *j*² is insulated therefrom. Therefore the current passes from the wire *i* through the trolley-arm *j* to contact *j*⁴, also through the trolley-arm *j*, wire *k*⁷, armature *k*⁴, which normally is in electrical communication with the wire *k*⁶ through said wire *k*⁶, lamp *k*⁵, and to the ground, as shown in Fig. 3, and the lamp *k*⁵, which is white, is thereby lighted. The current passing through the trolley-arm *j* and contact *j*⁴ and wire *i*² enters the electromagnet *f*² and to the ground by *m*⁸, and the armature *f*⁴ is thereby actuated, and the current passes through said armature, contact *h*⁸, wires *h*⁴ and *h*⁵ to dynamo *h*⁶. When this circuit is complete, the current also passes through the wire *g*², lamp *g*, and wire *g*³, which is in electrical connection with the armature *f*⁴, and the lamp *g* is thereby lighted. As will thus be seen, there are two complete circuits when a locomotive is in any one block, there being no cause for dangerous signals, one circuit through the locomotive lighting the white lamp *k*⁵ and the other circuit through the train-despatcher's office and lighting the lamp *g*, and the engineer and

train-despatcher are thereby notified that all is well. Should, however, a locomotive come into the block next to the rear, (in this case the block *a*₁) the trolley-arm *j* of this locomotive would engage the wires *i*³, *i*, and *i*² of this block, and the wires *i* and *i*² of the block *a*², being already in complete connection through the locomotive in the block *a*², the locomotive in the block *a* would be similarly connected; but the wire *i*³ of the block *a* is in electrical connection with the armature *f*⁴ of the electromagnet *f*², which is already in electrical operation. Therefore the current would pass through contact *j*² of the trolley-arm *j* of the locomotive in block *a*, through the trolley-arm *j*, wire *k*², and electromagnet *k* and to the ground through *m*, at which time the armature *k*⁴ is actuated and breaks the contact between the armature *k*⁴ and wire *k*⁶, and thereby extinguishes the white lamp *k*⁵, and the lamp *k*³, which is red, is thereby lighted and warns the engineer that a train is in the block next ahead. The current also flows through the wire *i*² of the block *a* by means of the contacts *j*³ and *j*⁴ to the electromagnet *f* in the train-despatcher's office, attracts the armature *f*⁴ of this electromagnet, and passes through said electromagnet to wires *h*⁴ and *h*⁵ and back to dynamo *h*⁶, and the lamp *g* of the electromagnet *f* is thereby lighted, and the train-despatcher seeing two lamps lighted knows that a train is in each of the blocks *a*² and *a*, and the current passing into the wire *i*³ of the electromagnet *f* is in readiness for operation with a locomotive which might come into the next block to the rear.

The lamp *g* of each electromagnet is energized when the circuit is complete between said electromagnet and its corresponding armature *f*⁴, as the wires *g*² and *g*³ of the lamp *g* of each electromagnet are electrically connected with the electromagnet and its corresponding armature, respectively.

When the locomotive *c* in the block *a*² passes into the block *a*₃, the first operation described is repeated, as will be readily seen, and the electromagnet *f*³ is then actuated, and the electromagnet *f*² is then out of electrical connection with the wire *i*, so the wire *i*³ of the block *a* is no longer energized, and the current of the segmental circuit is again completed, and the red light *k*³ in the locomotive in the block *a* is extinguished and the white lamp *k*⁵ lighted, and the lamp *g* of the electromagnet *f*³ in the train-despatcher's office is also extinguished, while the lamps *g* of the electromagnets *f* and *f*² are energized, and the train-despatcher knows thereby the position of each train which may be in any of the blocks.

It will be understood, of course, that the operation hereinbefore described is repeated or will be the same in any block or section of the system, and if a train at any time be on any block or section of said system and a sec-

ond train should enter the block or section preceding it the engineer of the second train will be at once notified that a train is on the preceding block or section, this notification being given as hereinbefore described.

Having fully described my invention, what I claim as new, and desire to secure by Letters Patent, is—

1. In a block-signal system for railways, a plurality of grounded electromagnets equaling in number the blocks or sections of the road, a main wire or conductor, a main return-wire having contact-points adjacent to said magnets, a pivoted armature adjacent to each of said magnets and means for making contact therewith and with the contact-points of the main return-wire, a signal adjacent to each of said magnets and adapted to be operated by the armature thereof, two supplemental wires in each block or section parallel with the main wire or conductor one of said supplemental wires in each block or section being in connection with one of said magnets and the other supplemental wire in each block or section being in connection with the armature of another of said magnets, substantially as shown and described.

2. In a block-signal system for railways, a plurality of grounded magnets equaling in number the blocks or sections of the road, a main wire or conductor, a main wire having contact-points adjacent to said magnets, a pivoted armature adjacent to each of said magnets and means for making contact therewith and with the contact-points of the main return-wires, a light adjacent to each of said magnets and adapted to be actuated by the armature thereof, two supplemental wires in each block or section parallel with the main wire or conductor one of said supplemental wires in each block or section being in connection with one of said magnets and the other supplemental wire in each block or section being in connection with the armature of another of said magnets, and a trolley-arm connected with the cab of a locomotive and provided with three trolleys, one of which is insulated therefrom, said trolleys being adapted to operate in connection with the main conductor-wire and the supplemental wires in each block or section, substantially as shown and described.

3. In a block-signal system for railways, a plurality of grounded magnets equaling in number the blocks or sections of the road, a main wire or conductor, a main return-wire having contact-points adjacent to said magnets, a pivoted armature adjacent to each of said magnets and means for making contact therewith and with the contact-points of the main return-wire, a light adjacent to each of said magnets and adapted to be actuated by the armature thereof, two supplemental wires in each block or section parallel with the main wire or conductor, one of said supplemental wires in each block or section being in connection with one of said magnets and

the other supplemental wire in each block or section being in connection with the armature of another of said magnets, and a trolley-arm connected with the cab of a locomotive and provided with three trolleys, one of which is insulated therefrom, said trolleys being adapted to operate in connection with the main conductor-wire and the supplemental wires in each block or section, and the cab of the locomotive being also provided with a grounded magnet and a light in connection therewith and with the insulated trolley, said magnet being also provided with an armature which is normally in connection with the trolley-arm and a light adapted to be actuated through said armature, substantially as shown and described.

4. An electric block-signal system for railways, comprising a main conductor-wire, a main return-wire, a plurality of grounded magnets equaling in number the blocks or sections into which a railway is divided, a pivoted armature adjacent to each of said magnets, means for making contact between said magnets and corresponding armatures two supplemental wires running parallel with the main conductor-wire in each of the blocks or sections, one of said supplemental wires in each block or section being in connection with the corresponding magnet and the other with the armature of another magnet, and means connected with the locomotive for closing the circuit through the supplemental wires, the magnets and the armatures, substantially as shown and described.

5. In an electric signal system for railways divided into blocks or sections, a plurality of grounded magnets, a pivoted armature adjacent to each of said magnets, means for making contact between said magnets and the corresponding armatures, a main conductor-wire, a main return-wire in connection with the contacts of said armatures, two supplemental wires in each block or section running parallel with the main conductor-wire, one of said supplemental wires in each block or section being in connection with one of said magnets and the other supplemental wire in said block or section being in connection with the armature of another of said magnets, and a trolley-arm connected with the locomotive and provided with three trolleys adapted to operate in connection with the main conductor-wire and the supplemental wires, one of said trolleys being insulated from said arm, substantially as shown and described.

6. In an electric signal system for railways divided into blocks or sections, a plurality of grounded magnets, a pivoted armature adjacent to each of said magnets, means for making contact between said magnets and corresponding armatures, a main conductor-wire, a main return-wire adapted to be connected with the armatures of said magnets, two supplemental wires in each block or section running parallel with the main conductor-wire, one of said supplemental wires in each block

or section being in connection with one of said magnets and the other supplemental wire in said block or section being in connection with the armature of one of said magnets and 5 a trolley-arm connected with the locomotive and provided with three trolleys adapted to operate in connection with the main conductor-wire and the supplemental wires, one of said trolleys being insulated from said arm, 10 the cab of the locomotive being also provided with a magnet in connection with the insulated trolley, a signal-light actuated thereby and another light actuated by the armature of said magnet which is in connection with 15 said trolley-arm, substantially as shown and described.

7. In a block-signal system for railways, a plurality of grounded electromagnets, a pivoted armature adjacent to each, means for 20 making contact between said magnets and corresponding armatures, a main conductor, a return-conductor provided with contact-points adjacent to one end of each of the pivoted armatures, and two supplemental wires 25 in each block parallel with said main conductor, one of said wires in each block being in connection with one of said magnets and the other in connection with the pivoted ar-

mature of one another said magnets, substantially as shown and described. 30

8. In a signal apparatus of the class described, a trolley-arm connected with the cab of the locomotive and provided with three trolleys one of which is insulated from the arm, 35 said trolleys being adapted to operate in connection with a three-wire circuit, the main return-wire of which is permanently grounded an electromagnet within the cab of the locomotive, said magnet being grounded, a wire connecting said magnet with the insulated 40 trolley, a signal connected with said wire, an armature pivotally supported adjacent to said magnet, a signal connected therewith and a wire connecting one end of said armature with the trolley-arm, said armature being 45 grounded through said last-named signal, substantially as shown and described.

In testimony that I claim the foregoing as my invention I have signed my name, in presence of the subscribing witnesses, this 25th 50 day of February, 1902.

WILLIS C. BRYANT.
